FIG. 1 is a perspective view of a dispensing container showing my new design with an extendible closure in an opened position;

FIG. 2 is a view similar to that of FIG. 1, except that the closure is in a closed position;

FIG. 3 is a front elevational view with the closure in a closed position;

FIG. 4 is a view similar to that of FIG. 3, except that the closure is in an opened position;

FIG. 5 is an elevational view looking from the right of FIG. 3; and

FIG. 6 is a top plan view.

The rear and bottom surfaces of the container are plain and unornamented.

I claim:

The ornamental design for a dispensing container, substantially as shown and described.
